UNITED STATES PATENT OFFICE.

LEO STEIN, OF ROCHESTER, NEW YORK, ASSIGNOR TO THE STEIN MANUFACTURING COMPANY, OF SAME PLACE.

DESIGN FOR A BURIAL-CASKET.

SPECIFICATION forming part of Design No. 17,928, dated December 6, 1887.

Application filed May 20, 1887. Serial No. 238,923. Term of patent 14 years.

To all whom it may concern:

Be it known that I, LEO STEIN, of Rochester, in the county of Monroe, in the State of New York, have invented a new and original 5 Design for Burial-Caskets, of which the following, taken in connection with the accompanying drawings, is a full, clear, and exact description.

My invention relates to a new and original 10 design for burial-caskets; and it consists, essentially, of the design for the ornamental molding herein described and claimed.

In specifying my design, reference is had to the accompanying drawings, forming part of 15 this specification, in which—

Figure 1 is an isometric view showing my 20 design applied to a burial-casket, and Fig. 2 is an enlarged detached view of the ornamental molding and ogee, these two views being deemed essential to illustrate my design.

The leading feature of my design consists in arranging an ornamental border-molding 25 formed of fluted serrations having curved bottom and straight top ends, and curvilinear in cross-section at the top of the ogee molding of a burial-casket, thus securing a novel and pleasing combined effect of horizontal and vertically-curved planes rising one above the other in easy and graceful lines.

30 A denotes the casket, which may be of any desirable form or material.

a is the ornamental molding applied to the casket at the top of the ogee *b*. The molding *a* is composed of the serrated or fluted ribs *c*, arranged in a vertical direction in relation to 35 the molding *a* and curving gracefully from the top of the ogee *b* to the top of the molding *a*.

The moldings are shown applied to the casket *A*, as shown in Fig. 1. The upper molding and ogee are shown in close proximity to 40 the top of the casket, the top of the molding *a* forming the base or support for the casket-lid, and the lower molding extends around the base of the casket, as shown in Fig. 1 aforesaid.

What I claim as new, and desire to secure 45 by Letters Patent, is—

A design for a burial-casket having the molding *a*, composed of curved flutes or serrations *c*, curved at bottom and straight at top, and combined with the ogee *b*, substantially as shown 50 and described.

In testimony whereof I have hereunto signed my name, in the presence of two attesting witnesses, at Rochester, in the county of Monroe, in the State of New York, this 6th day of May, 55 1887.

LEO STEIN.
